tion of Delaware

Application February 10, 1948, Serial No. 7,393

12 Claims. (Cl. 226—2)

1

This invention relates to improvements in bag-filling machines and more particularly to a machine for filling a bag of the open-mesh, draw-string type with a predetermined number of articles such as citrus fruit, vegetables or the like.

The various objects and advantages of the invention will be best understood from the following description and the accompanying drawings in which:

Fig. 1 is a plan view of a portion of a bag-filling machine embodying the invention;

Fig. 2 is a front view of the mechanism shown in Fig. 1 with certain parts omitted for clarity;

Fig. 3 is a side view taken from the left of the mechanism shown in Fig. 1 with certain parts omitted for clarity;

Fig. 4 is a side view of another portion of a bag-filling machine embodying the invention;

Fig. 5 is a plan view of the mechanism shown in Fig. 4;

Fig. 6 is a perspective view showing the details of a portion of the machine illustrated in Fig. 1;

Fig. 7 is a plan view showing the details of the driving mechanism for the apparatus shown in Fig. 6;

Fig. 8 is a side elevation showing the details of another portion of the machine illustrated in Fig. 1;

Figs. 8a, b and c illustrate the operation of the mechanism shown in Fig. 8;

Fig. 9 is a plan view of apparatus shown in Fig. 8;

Fig. 10 is a side view of apparatus shown in Fig. 8;

Fig. 11 is a side view in partial section showing certain details of the drive for the apparatus illustrated in Figs. 1, 2 and 3;

Fig. 12 is a plan view showing certain details of a bag holder;

Fig. 13 is a section view taken along the line 13—13 of Fig. 11; and

Fig. 14 is a section view taken along the line 14—14 of Fig. 11.

Referring particularly to Figs. 1, 2 and 3, there is a turret head 10 with four equidistantly spaced arms 11. At the ends of each of the turret arms 11 there is a bag holder 12, which will be described more fully hereinafter, to which a bag 13 may be secured in a position to receive the fruit or other articles that are to be placed in the bag.

The turret head arms 11 are rotatably supported on the central support or shaft 14 and extend radially therefrom. The arms 11 are rotated in a clockwise direction, as shown in Fig. 1, about the shaft 14 and in intermittent steps by

2

a Geneva movement. Forming part of the Geneva movement there is a star wheel 15 rotatably mounted on the central shaft 14 and to which the arms 11 are secured by studs 16, as shown in Fig. 1, 2 or 3. The star wheel 15 has four equidistantly spaced slots 17 that are periodically engaged by a roller 18 carried by a rotating arm 19. The engagement of the roller 18 with one of the slots causes the star wheel 15 and the turret head arms 11 to be racked around one-quarter turn in a clockwise direction.

The rotating arm 19 carrying the roller 18 is secured to a rotating member 20 that is fastened to a vertical drive shaft 21 supported alongside of the central support or shaft 14. A bevel gear 22 secured to the vertical shaft 21 meshes with a second bevel gear 23 secured to a horizontal drive shaft 24. The horizontal shaft 24 is supported by a bearing block 25. The bearing block 25 is supported on the shaft 21 and is also connected to a collar 25a on the central support 14 by a pin 25b. A pulley 26 secured to one end of the horizontal shaft is engaged by a driving belt 27. The belt 27 is driven by a pulley 28 on the main drive shaft 29 which is driven through reducing gears 30 by an electric motor 31.

The periphery of the star wheel 15 between the slots 17 is arcuate having a radius slightly greater than the radius of the rotating member 20 so as to permit the member to rotate relative to the star wheel during the period that the roller is out of engagement with the slots 17. This also holds the star wheel and the turret head arms stationary during the time that the roller 18 is completing a revolution to engage the next slot after moving the star wheel one-quarter turn. The rotating member 20 is cut away beneath the arm 19 carrying the roller 18 to receive the slotted portions of the star wheel and permits the star wheel to turn as the roller 18 engages with one of the slots.

When the turret head arms 11 are driven in the manner just described, they are progressively advanced in a clockwise direction in intermittent steps to the stations indicated at I, II, III and IV in Fig. 1. At each of these stations, the turret head arms remain stationary for a certain interval of time during which individual operations are being performed at each of the stations. The various operations performed at these stations will be described more fully hereinafter but briefly they are as follows: at station I the bag 13 is placed on the bag holder 12; at station II a predetermined number of fruit or vegetables are fed into the bag; at station III the bag is closed;

and at station IV the bag is tied and discharged from the machine. A bag in being filled passes through the operations at each of the stations in a complete operating cycle of the machine.

The bag 13 which has a drawstring 32 and which may be of the mesh type is placed on the bag holder 12 at station I by the operator. The bag holder 12 consists of a funnel 33 supported by a plate 34 fixed to the arm 11. Leaf springs 35 carried by the plate 34 and spaced about the funnel, press against the outer side walls of the funnel 33. The mouth of the bag is inserted between the leaf springs and the funnels so that the leaf springs hold the empty bag in place temporarily. When the bag is placed on the holder, the drawstring 32 is secured to a hook 36 carried on the outer end of the turret arm 11.

As the turret arm 11 carrying the empty bag 13 moves from station I to station II, a fixed cam follower 37 strikes a lever 38 pivoted on a stud 39 fixed to the plate 34. The other end of the lever 38 engages with a stud 40 secured to a cam plate 41 which is movably supported on the plate 34. The cam plate 41 is operatively connected to four crank levers 42 which are carried by the plate 34 and are spaced about the outside of the funnel 33. The crank levers 42 have grippers 43 at their ends which are arranged to extend into openings 44 in the side walls of the funnel 33.

When the cam follower 37 strikes the lever 38, it moves the lever and the cam plate 41 through a small angle relative to the plate 34. The movement of the cam plate in this manner rotates the cranks 42 so that the grippers 43 engage with or pass through the bag 13 and extend into the appropriate openings 44 in the sides of the funnel 33. The engagement of the grippers with the bag in this manner secure the bag to the bag holder for filling and movement of the filled bag to a subsequent station.

At station II the bag 13 is filled with a predetermined number of fruit, vegetables or the like from two downwardly sloping parallel chutes or hoppers 45 shown in Figs. 4 and 5. The chutes or hoppers 45, as shown by the dotted lines in Fig. 3, are placed so that they discharge the fruit into the opening of the funnel 33 and the bag held thereby which are on the end of the turret arm positioned at station II. The chutes 45 are identical and have similar counting mechanisms operating in conjunction therewith except that one is right-handed and one is left-handed. For the sake of simplicity, only the operation of the right-hand unit will be described below.

As the turret arm 11 approaches station II, a cam 46 carried at the outer end of the plate 34 on the turret arm strikes and depresses a lever 47. The lever 47 is secured to a rock shaft 48 to which a release lever 49 is secured. The depression of the lever 47 imparts a slight outward movement to the release lever 49 which abuts a pin 50 on a detent 51 and a pin 52 on a pawl 53. The detent 51 is pivoted on a panel 54 and is held in engagement with a ratchet wheel 55 by a spring 56. The pawl 53 is pivoted on the end of a lever 57 pivoted on the panel and the pawl is held in engagement with the ratchet wheel by a spring 58.

The outward movement of the release lever 49 lifts the detent 51 and the pawl 53 from engagement with the ratchet wheel 55 and permits the ratchet wheel to be rotated in a counterclockwise direction by a spring 59 until a pin 60 carried on the inside of the ratchet wheel, strikes a stop 61 secured to the panel 53 and thus returns the ratchet wheel to its starting position. The lever 57 is also connected to a paddle stopping lever

62 through a collar 63 and a link 64. The link 64 is connected to a lever 65 that is secured to a rock shaft 66 to which the stop lever 62 is secured by an arm 67. The downward movement of the lever 47 moves the stop lever 62 into position to engage an arm 68 of a paddle wheel 69.

The paddle wheel 69 is secured to a shaft 70 supported below the chute 41 by a frame 71 and the arms 68 of the paddle wheel extend through a slot 72 in the bottom of the chute to engage with the articles passing through the chute. The operation of the paddle wheel is controlled through the ratchet wheel 50, in a manner to be described, but when the ratchet wheel is being returned to starting position, the stop lever 62 prevents the paddle wheel from turning and thus prevents the discharge of articles from the chute at such time.

As the turret head arm 11 reaches station II, the cam 46 releases the lever 47 permitting the detent 51 and the pawl 53 to be reengaged with the ratchet wheel 55 under the influence of springs 56 and 58, respectively. This also moves the stop lever 62 from engagement with the arm 68 of the paddle wheel 69 and permits the paddle wheel to be turned by the weight of the articles passing down the chute and discharging into the bag held by the turret arm at station II.

As the paddle wheel 69 rotates, it turns the shaft 70 to which a wheel 73 is secured. The wheel 73 has lugs 74 extending radially therefrom and corresponding in number to the arms 68 of the paddle wheel. As the wheel 73 rotates, the lugs 74 strike an arm 75 carried by the lever 57 and raise the lever 57 from a position where it is held against a stop 76 by a spring 77. The movement of lever 57 in this manner moves the pawl 53 downwardly and racks the ratchet wheel 55 around one step. When the lug 74 releases the arm 75, the lever 57 is returned by the spring 77 and the pawl is moved back into engagement with the following tooth on the ratchet wheel. As the pawl is being moved back in this manner, the detent 51 holds the ratchet wheel in its advanced position.

This operation continues until the ratchet wheel has been advanced a predetermined number of teeth corresponding to the number of articles required to fill the bag. After the ratchet wheel has been advanced the predetermined number of teeth, an adjustable pin 78 carried on the outer side of the ratchet wheel strikes a stop 79 held by an arm 80 which is supported in fixed position from a shaft 81 on which the ratchet wheel turns. When the pin 78 strikes the stop 79, the pawl 53 is held against further movement by the ratchet wheel and this prevents lever 57 from being lifted by the lugs 74 and prevents the paddle wheel from turning and fruit from being discharged from the chute until the ratchet wheel is reset to starting position by the next movement of the turret head.

The adjustable stop pin 78 may be placed in any one of a series of holes 82 spaced about the ratchet wheel so as to regulate the distance that the ratchet wheel can be racked around and thereby set the mechanism to discharge from the chutes the number of articles that, depending on their size, will be required to fill the bag.

As the fruit falls into the bag, the bag and any fruit contained therein are jogged to settle the fruit in the bag to the least possible volume so as to insure that all of the fruit will remain in the bag when the drawstring is drawn to close the mouth of the bag. This jogging is done by a plate 83, shown best in Fig. 3, which is sup-

ported underneath the bag being filled at station II by a lever 84. The lever 84 is pivoted on a stud 85 and its end engages with a cam 86 which is rotated by the main drive shaft 29. This imparts an oscillating motion to the plate 83 bringing it into and out of engagement with the bag during the filling operation.

The turret arm 11 carrying the filled bag is then moved to station III where it is again stopped momentarily. Shortly after leaving station III, on the next movement of the turret arm, a fixed cam follower 87 strikes a second lever arm 88 which is pivoted on the stud 39 below the lever 38. An end of the lever 88 is secured to the cam plate 41 and moves the cam plate in an opposite direction to the rotation caused by the lever 39. This rocks the crank 42 so as to withdraw the grippers 43 from the openings 44 in the side walls of the funnel 33 and from engagement with the bag.

When the bag is released in this manner, the filled bag slips off of the bag holder 12 and falls by its own weight until the bottom of the bag rests on a platform 89. When the bag falls to the platform, the drawstring 32 is retained by hook 36 and is pulled tight so as to close the mouth of the bag.

The platform 89 is rockably supported at one edge on an axle 90 and is held in a horizontal position by a loaded spring 91 which surrounds the axle and bears against the under side of the platform 89. The axle 90 and the platform 89 are supported by rods 92 extending upwardly from a supporting framework 93. The upward movement of the platform 89 under the influence of the loaded spring 91 is limited by a stop 94 that is secured to one of the supporting rods 92. The stop 94 holds the platform at a substantially horizontal position and prevents it rising above that position. As the arm continues to move, the bag is slid toward the unsupported edge of the platform 89 which tilts downward to an angle of about 45° and drops the bag into a discharging hopper 95. When the bag is removed, the platform 89 is returned to horizontal position by the spring 91.

As the turret arm 11 moves from station III to station IV, the drawstring 32 is guided inside of a guide 96 and along the outer edge of a curved plate 97. The guide 96 is supported on a rod 98 from a bracket 99 and the plate 97 is supported on a knot tying mechanism 100 as shown best in Figs. 8, 9 and 10. The guide 96 and the plate 97 position the drawstring 32 so that it passes behind a spring-held guide 101 as it moves along the plate 97. The spring-held guide 101 is pivoted at 102 on a plate 99a and an arm 103, also supported on the plate 99a, is opposed to the guide 101 at its inner end. As the drawstring enters behind the guide 101, the guide rotates through a small angle until the drawstring 32 moves to a position where the guide is permitted to return to its closed position. When the turret arm 11 reaches station IV, the lower end of the drawstring is thus held between the spring-held guide 101 and the lever 103 in engagement with a rotatable knotter head. The rotatable knotter head has a hooked finger 105 and a finger 104 pivotally mounted on the knotter head in opposed relation to the hooked finger 105. As shown best in Fig. 8, the drawstring 32 extends in back of the ends of the hooked finger 105 and the pivoted finger 104 and in front of the shanks thereof when the bag reaches station IV. Thus, when the knotted head is rotated the fingers 104

and 105 engage with the downwardly extending portion of the drawstring and wrap the drawstring around the shanks of the knotter fingers.

The knotter finger 104 that is pivotally supported at 104a on the knotter head is normally urged into engagement with the hooked finger 105 by a spring 104b. The end of the pivoted knotter finger 104 engages with a fixed cam 118 that is shaped to move the pivoted finger 104 away from the hooked finger 105 at an appropriate time to permit the upwardly extending portion of the drawstring 32 to enter between the knotter fingers as they are rotated.

The rotatable knotter head is secured to a shaft 106 that is rotatably supported in spaced bearings 107 mounted on the bracket 99. A bevel gear 108 secured to the knotter shaft 106 is intermittently driven in timed relation to the operation of the machine by a bevel gear 109 secured to a cross shaft 110 and, as shown best in Figs. 3 and 9, the cross shaft 110 has a second bevel gear 111 secured thereto that is driven by a bevel gear 112 secured to a vertical drive shaft 113. As shown best in Figures 3 and 7, the drive shaft 113 is driven through a spur gear 114 that meshes with a gear 115 rotatably mounted on the central support 14. The gear 115 is secured to an intermittent gear 116 that is driven by gear segment 117 secured to the shaft 21 as shown in Figs. 13 and 14. The segmental gear 116 and the gear 115 secured thereto are turned one-third of a revolution by the gear segment 117 for each revolution of the shaft 21. The ratio of the gear 115 and the spur gear 114 is 3 to 1 so that the shaft 113 and thus, the knot tying mechanism 100, is rotated a complete revolution for each movement of the gear 115 and for each complete revolution of the shaft 21. As previously explained, the turret arms are also moved one quarter turn for each revolution of the shaft 21.

By the arrangement just described, the knotter fingers 104 and 105 are rotated through 360° after the filled bag arrives at station IV. When the knotter fingers 104 and 105 are rotated clockwise as viewed in Fig. 10, they engage the portion of the drawstring 32 extending below the center line of the shaft 106 and loop the drawstring about the knotter fingers 104 and 105 as previously described. During the continued rotation, the finger 104 is opened by the fixed cam 118 and the unlooped portion of the drawstring 32 enters between the fingers 105 and 104. At the proper time the cam 118 releases the finger 104 so that the unlooped portion of the drawstring is held between the knotter fingers 104 and 105 and is positioned behind a projection 104c on the pivoted finger 104.

As the knotter turns, the hopper 95 is raised slowly to place the proper tension on the drawstring and to permit the loop to be formed around the knotter fingers 104 and 105. As shown best in Fig. 6, the hopper is supported on arms 119a which are secured to an axle 119. The axle 119 is journalled in bearings 120 and a lever 121 is secured to the end of the shaft. The lever 121 is connected by a linkage 122 to an oscillating shaft 123. The shaft 123 is held by a bracket 124 which is secured to the central shaft 14 and has an arm 125 fixed to its end. The arm 125 carries a follower 126 which is periodically engaged by one of a pair of rollers 127 carried on a rotating gear 128. When one of the rollers engage with the follower 126, the follower is rocked through a small angle thereby rocking the shaft 123 and the hopper carrying axle 119 in a direction to raise the hopper.

The gear 128 carrying the rollers 127 is rotatably mounted on a stud 129 which is supported on a bracket 130 extending from the bearing block 25. The gear 128 is driven by a pinion gear 131 which is secured to the bevel gear 22. The ratio of the gear 128 to the pinion gear 131 is 2 to 1 so that the gear 128 makes a complete revolution for two revolutions of the shaft 21 and during each half revolution of the gear 128, one of the rollers 127 engages with the follower 126 to raise the hopper in properly timed relation to the operation of the knotter.

After the drawstring 32 has been wrapped around the knotter fingers 104 and 105 and the unlooped portion of the drawstring grasped between the knotter fingers, the drawstring is disengaged from the hook 36 on the turret head arm by an arm 132. The arm 132 is secured to a sleeve 133 which is pivoted on a stud 134 extending from the frame 99. The arm 132 is biased out of engagement with the drawstring under spring tension and is moved into engagement with the drawstring at appropriate time by a lever 135 which is secured to sleeve 134. The end of the lever 135 is periodically engaged by studs 136 carried by the gear 116. When the lever 135 is in released position, it returns under spring tension to a position against a stop 137.

When the drawstring has been disengaged from the hook, the hopper 95 is lowered and as illustrated in Fig. 8b, the weight of the filled bag pulls the portion of the drawstring that has been wrapped around the knotter fingers 104 and 105 off of the knotter fingers with the unlooped portion of the drawstring 32 held between the knotter fingers 104 and 105. As illustrated in Fig. 8c, when the portion of the drawstring 32 wrapped around the knotter fingers 104 and 105 slips off of the knotter fingers, it passes over a doubled end or loop formed by the unlooped portion held by the knotter fingers and the free end of the drawstring so that a loop is formed with a knot below it. The knot is thereafter drawn tight under the weight of the bag. This forms a bow knot in which the length of the loop is determined by the distance of the projection 104c from the end of the knotter finger 104. As the pull on the knotted drawstring is continued the loop of the knot snaps out from between the knotter fingers 104 and 105.

As the hopper continues to lower, a spring held arm 138 engages with the bottom of the hopper on one side and causes the hopper to tilt about hinges 139 which secure the hopper along its other side to one of the supporting arms 119a. The tilting of the hopper causes the filled bag to slide clear of the machine and onto the floor or a conveyor belt if one is provided. As the hopper tilts, it finally reaches a position where it clears the arm 138 and is permitted to return to its initial position. In returning to its initial position, the hopper pushes the spring held arm 138 back against a compression spring 140 which presses against the arm 138 through a rod 141 and a collar 142. The arm 138 is pivoted at 143 in a bracket 144.

It will be understood that the various operations described above are being performed simultaneously at each of the stations when the machine is in operation. It will also be understood that various changes and modifications in the mechanism described and illustrated may be made by those skilled in the art without departing from the scope of the invention as defined by the appended claims.

What is claimed is:

1. In a bag-filling machine of the class de-

scribed, the combination comprising a rotatable knotter head including a hooked finger, a movable finger pivotally supported on the knotter head in opposed relation to said hooked finger and a spring holding said movable finger in engagement with the hooked finger, said fingers being positioned to engage with a drawstring of a filled bag and a fixed cam engaging with the movable finger, said cam being designed to move said movable finger away from the hooked finger to permit the drawstring of the bag to enter between the fingers during rotation of the knotter head.

2. In a bag-filling machine of the class described, the combination as defined in claim 1 wherein a projection carried by the movable finger extends between the fingers when they are in engagement, said projection engaging with the portion of the drawstring held between the fingers to form an elongated loop of a bow knot.

3. In a bag-filling machine of the class described, the combination as defined in claim 1 including a hopper located beneath the knotter head for supporting the bag with its drawstring in engagement with the fingers on the knotter head and means for raising and lowering said hopper as the knotter head is rotated.

4. In a bag-filling machine of the class described, the combination of a rotatable knotter head including a hooked finger, a movable finger pivotally supported on the knotter head in opposed relation to the hooked finger, a spring normally holding the movable finger in engagement with the hooked finger and a member carried by one of said fingers and extending between the fingers when they are in engagement, said fingers being positioned to engage with a drawstring of a filled bag when the knotter head is rotated, a fixed cam engaging with the end of the movable finger, said cam being designed to open the fingers to permit the drawstring to enter the fingers as the knotter head is rotated, a hopper located beneath the knotter head for supporting the filled bag with its drawstring in engagement with the fingers of the knotter head and means for raising and lowering the hopper during the rotation of the knotter.

5. In a bag-filling machine of the class described, the combination as defined in claim 4 including a guide engaging with and positioning the drawstring for engagement by the fingers of the knotter head.

6. An apparatus of the type described for filling a bag having a drawstring closure with a predetermined number of articles, closing the mouth of the bag, tying the drawstring and discharging the filled bag, the combination which includes a series of radially extending arms rotatable as a unit about a fixed axis, a member carried at the end of each of said arms for supporting a bag in open-mouthed position on each of said arms, said members including grippers engaging with the sides of the bag, operating levers connected to the grippers and a drawstring-engaging member engaging with the drawstring of the bag, an intermittent-movement connected to said arms for moving the arms as a unit about the fixed axis and positioning the arms sequentially at a series of spaced positions, a feed mechanism located at one of said positions for delivering a predetermined number of articles to the bag at said position, cams engaging with and operating the gripper-operating levers upon movement of the arms, said cams being positioned to bring the grippers into engagement

with the sides of the bag prior to the bag-filling position of the arms and to release the grippers from engagement with the bag at the position of the arms following said bag-filling position, a pivoted platform located beneath the filled bag at said bag-releasing position, said platform being tiltable downwardly under the weight of the filled bag, a reciprocating hopper located at the position of the arms following said bag-releasing position, said hopper being positioned to receive the filled bag from said tiltable platform upon movement of the arms, a knotting mechanism positioned to engage with the drawstring of the bag as the bag is moved from the platform to the hopper, means for operating said knotting mechanism to tie a knot in the drawstring and means for simultaneously raising the hopper during operation of the knotting mechanism.

7. An apparatus of the type described for filling a bag having a drawstring closure with a predetermined number of articles closing the mouth of the bag, tying the drawstring and discharging the filled bag, the combination of a series of radially extending arms, said arms being rotatable as a unit about a fixed axis, a member carried at the end of each of said arms for supporting a bag in open-mouthed position on each of said arms, said members including grippers engaging with the sides of the bag, operating levers connected to the grippers and a drawstring-engaging member engaging with the drawstring of the bag, an intermittent movement connected to said arms for moving the arms as a unit about the fixed axis and positioning the arms sequentially at a series of spaced positions, a feed mechanism located at one of said positions for delivering a predetermined number of articles to the bag at said position, cams engaging with and operating the gripper-operating levers upon movement of the arms, said cams being positioned to bring the grippers into engagement with the sides of the bag prior to the bag-filling position of the arms and to release the grippers from engagement with the bag at a position of the arms following said bag-filling position, a pivoted platform located beneath the filled bag at said bag-releasing position, said platform being tiltable downwardly under the weight of the filled bag, a reciprocating hopper located at a position of the arms following the bag-releasing position, said hopper being positioned to receive the filled bag from said tiltable platform, a knotting mechanism engaging with the drawstring of the bag as the bag is moved from the platform to the hopper, means for operating said knotting mechanism to tie a knot in a drawstring and means for raising the hopper as the knot is being tied.

8. An apparatus of the type described for filling a bag having a drawstring closure with a predetermined number of articles, closing the mouth of the bag, tying the drawstring and discharging the filled bag, the combination of a series of radially extending arms, said arms being rotatable as a unit about a fixed axis, a member carried at the end of each of said arms for supporting a bag in open-mouthed position on each of said arms, said members including grippers engaging with the sides of the bag, operating levers connected to the grippers and a drawstring-engaging member engaging with the drawstring of the bag, an intermittent movement con-

nected to said arms for moving the arms as a unit about the fixed axis and positioning the arms sequentially at a series of spaced positions, a feed mechanism located at one of said positions, said feed mechanism being capable of delivering a predetermined number of articles to the bag at said position, means for initiating operation of said feed mechanism, said means being operable by the bag-supporting arms in their movement from one position to the next position, cams engaging with and operating the gripper-operating levers upon movement of the arms, said cams being positioned to bring the grippers into engagement with the sides of the bag prior to the bag-filling position of the arms and to release the grippers from engagement with the bag at a position of the arms following said bag-filling position, a pivoted platform located beneath the filled bag at said bag-releasing position, said platform being tiltable downwardly under the weight of the filled bag, a reciprocating hopper located at a position of the arms following the bag-releasing position, said hopper being positioned to receive the filled bag from said tiltable platform, a knotting mechanism engaging with the drawstring of the bag as the bag is moved from the platform to the hopper, means for operating said knotting mechanism to tie a knot in a drawstring and means for raising the hopper as the knot is being tied.

9. An apparatus of the type described for filling a bag having a drawstring closure with a predetermined number of articles, closing the mouth of the bag, tying the drawstring and discharging the filled bag, the combination of a series of radially extending, bag-supporting arms, said arms being rotatable as a unit about a fixed axis, means on said arms for securing a bag in open-mouthed position at the ends thereof, said means being operable by movement of the arms to secure the bag to the arms and to release the bag from said arms, means on each of said arms for holding a bag closing drawstring, an intermittent movement connected to said arms for moving the arms as a unit about the fixed axis and positioning the arms sequentially at a series of spaced positions, means for feeding a predetermined number of articles to the bag at one of said spaced positions, transferring means for receiving a filled bag at a second of said positions upon release of the filled bag from the bag-supporting arm at said position, a reciprocable hopper located at a third of said positions, said hopper being positioned to receive the filled bag from said transferring means, a knotting mechanism engaging with the drawstring of the bag as the arms move from the second to the third of said spaced positions, means for operating the knotting mechanism to tie a knot in the drawstring at said third position and means for raising the hopper as the knotting mechanism is operated.

10. In a bag-filling apparatus of the type described wherein a series of bags having drawstring closures are supported in open-mouthed position at the ends of a series of rotatable arms and are moved by said arms in intermittent steps through a series of spaced positions where the operations of filling the bag, closing the filled bag, tying the drawstring and discharging the bag are performed simultaneously at each of said positions and in sequence on the individual bags, the combination of a feed mechanism for delivering a number of articles to a bag at the first of said positions, means for initiating operation of said

11

feed means by movement of the bag-supporting arms in moving the bag to said first position, a pivoted platform positioned beneath a filled bag at the second of said positions for receiving a filled bag from one of the arms at said position, said platform being tiltable downwardly under the weight of the bag, a reciprocable hopper located at the third of said positions, said hopper being positioned to receive the filled bag from said platform and a knotter located at said third position for tying the drawstring of the filled bag.

11. In a machine for filling a drawstring type of bag and tying the drawstring of the bag after filling, the combination which includes means for tying a knot in a drawstring closing a bag, said means including a rotatable knotter head engaging with the drawstring of the bag, a vertically reciprocable hopper located beneath the knotter head, said hopper supporting the bag thereon with the drawstring in position for engagement with the knotter head and drive means for rotating said knotter head and raising the hopper as said knotter head is rotated.

12. In a machine for filling a drawstring type of bag and tying the drawstring of the bag after filling, the combination which includes means for tying a knot in a drawstring closing a bag, said means including a rotatable knotter head engaging with the drawstring of the bag, a vertically

5

reciprocable hopper located beneath the knotter head, said hopper being pivoted along one side thereof and supporting the bag thereon with the drawstring in position for engagement with the knotter head, drive means for rotating said knotter head and raising the hopper as said knotter head is rotated and a member positioned to engage with and to tilt the hopper about its pivoted side as the hopper returns from its raised position.
